UNITED STATES PATENT OFFICE.

ELMER U. AMES, OF PHILADELPHIA, PENNSYLVANIA, ASSIGNOR TO H. BRINTON COMPANY, OF PHILADELPHIA, PENNSYLVANIA, A CORPORATION OF PENNSYLVANIA. YARN-PUSHER FOR KNITTING-MACHINES.

1,335,633.

Specification of Letters Patent. Patented Mar. 30, 1920.

Application filed August 26, 1916. Serial No. 117,097.

To all whom it may concern:

Be it known that I, ELMER U. AMES, a citizen of the United States, residing in Philadelphia, Pennsylvania, have invented 5 Yarn-Pushers for Knitting-Machines, of which the following is a specification.

One object of my invention is to provide novel means for insuring the engagement of the yarn by a predetermined needle when 10 the machine is started after the transfer operation, which means, in addition to being simple in construction and certain in its operation, shall have no injurious or objectionable effects upon the needles or upon 15 any other part of the apparatus.

I further desire to provide a compact and substantial device for automatically pushing the yarn toward the needle cylinder of a knitting machine at a predetermined time 20 in the cycle of operation of the latter in order to insure the engagement of said yarn by a definite one of the needles when such engagement would otherwise be uncertain.

These objects and other advantageous ends 25 I secure as hereinafter set forth, reference being had to the accompanying drawings, in which,

Figure 1 is a side elevation of a part of 30 a knitting machine embodying my invention;

Fig. 2 is a plan of the machine shown in Fig. 1;

Fig. 3 is a fragmentary plan of a part 35 of the latch ring illustrating the operation of my invention;

Fig. 4 is a fragmentary elevation showing on a reduced scale certain of the parts illustrated in Fig. 2;

Fig. 5 is a perspective view of my yarn 40 pusher; and

Figs. 6, 7 and 8 are side elevations, partly in section, illustrating the operation of the pusher.

As is customary in machines of the type 45 illustrated, as well as in machines of a kindred type in which the cam ring is rotated and the needle cylinder is stationary, there is provided above the needle cylinder a latch ring 46 having a throat portion 47 in which the yarn serving fingers or guides 50 48, 49, 50 and 51 are mounted so that in

the present case they are movable in parallel vertical planes. Said guides are actuated by a series of slides 52, 53, 54 and 55 which are movable in the throat toward and from 55 the needle cylinder and each of them is acted on by a spring 56 so that it tends to move away from the cylinder, thereby drawing the yarn serving end of its finger into its lower or operative position.

The rear projections of these various slides are actuated from a cam drum 30 through cam levers 57, 58, 59 and 60, arranged as described and claimed in my pending application for a Patent #7,111, filed 65 February 9, 1915, and in the present case in addition to the above described parts, I provide a cam lever 61 actuated by a suitably placed cam 62 on the drum 30. Said lever acts on a slide 63 movable between 70 the slides 52 and 53 and like the latter, at all times tends to move away from the needle cylinder under the action of a spring 56 operative between a part of the latch ring 75 structure and a post 64.

This slide 63 has projecting forwardly from its front edge a pusher in the form of a finger (Fig. 5) whose forward end, in addition to having its top edge forwardly beveled, has at one side a notch 66 formed by 80 making an inclined vertical cut from the center of its front end to one side, the cut extending at an angle of about 30° to said side. It is noted that this cut does not extend completely through the finger but approaches the bottom thereof sufficiently to form a relatively narrow lip 67 whose lower edge is designed to slide in engagement with the upwardly curved surface of the front portion 68 of the bottom of the latch ring 90 throat, as shown in Figs. 7 and 8.

While the slides 52, 53, etc., are provided with parallel sided guide slots 69, the pusher slide 63 has similar longitudinally extending slots 70 which are larger at the rear ends 95 than at their forward portions, and through the two sets of slots of all the slides I extend a pair of guide and retaining pins 71 and 72 mounted in the side walls of the throat. As a result of this construction, when the slide 100 63 is moved forward and its pusher 65 strikes the upwardly curved bottom 68 of

the throat, said slide is free to have its forward end with the pusher tilted upwardly as the latter follows the top surface of said bottom and finally passes over the same under 5 the hooks of the needles into its extreme forward position shown in Fig. 6, within the outer circle defined by the outermost parts of said needles.

Under conditions of use, when a stocking 10 has been finished, the various yarn fingers 48, 49, 50 and 51 are all raised in the well known manner by the cams on the drum 30, acting through their various cam levers and slides 52, 53, 54 and 55. The succeeding revolution 15 of the needle cylinder thereupon runs the stitches off the needles and suitable mechanism forming no part of the present invention moves the belt shifter 6 and changes the belt to the loose pulley. 20 After the usual transfer operation the latch ring is dropped and the belt shifter is moved to cause the machine to be driven by power. At this time the right hand yarn finger 51 is lowered by its suitably placed 25 cam on the drum acting through the cam lever 60 and the slide 55, and the yarn so served is engaged by the short butt needles, from which it passes into the throat of the latch ring to said finger. The upper center 30 cam 35 is now moved inwardly far enough to engage the butts of the long butt needles so that these will be successively lowered, but the engagement of the yarn by the first 35 of these needles is by no means certain because of the angle at which it extends from the short butt needles. According to my invention however, the yarn pusher slide 63 with the pusher 65 now moves toward the needles under the action of the cam 62 and 40 the cam lever 61, causing the lip 67 of said pusher to engage the yarn as it leads from the finger 51 over the throat plate 68 and positively move it under the hook of the first 45 of the long butt needles, thus absolutely insuring its engagement thereby as said needle is lowered. After such engagement has occurred, the cam on the drum 30, which has actuated the pusher slide with the pusher, allows the latter to drop back to the normal 50 position shown in Fig. 7.

The machine thereafter continues its operation in the ordinary manner until the stocking is finished.

From the above description and illustrations 55 it will be understood that the pusher acts on that part of the yarn which runs from one of the short butt needles tangent to the circular series of needles, and bends it in toward the latter so that the first of the long 60 butt needles will certainly engage it. In so doing the thin lip of the pusher moves toward the needle cylinder in contact with the upwardly inclined throat plate, thereby effectually preventing the possibility of the

yarn slipping under it since said yarn extends in a line at an angle with the inclined bottom of said plate and is elevated above it. Said arm is thus held in its inwardly deflected position until it has been engaged by the proper needle. 65 70

I claim:—

1. The combination in a knitting machine of a circular series of needles; and means movable to a point inside of the circle defined by the outer parts of the hooks of said needles for projecting the yarn into position to be positively engaged by said hooks. 75

2. The combination in a knitting machine of a circular series of needles; a latch ring; means for serving yarn to the needles; and means movable under the hooks of said needles for insuring engagement of the yarn thereby. 80

3. The combination in a knitting machine of a circular series of needles; with a yarn pusher movable toward and from said needles and consisting of a bar having a single yarn engaging lip presenting a relatively sharp edge extending up and back from the bottom of its forward end in position to pass under and deliver the yarn to the hooks of the needles. 85 90 95

4. The combination in a knitting machine of a circular series of needles; a latch ring having a throat including a bottom portion; means for guiding yarn across said bottom portion to the needles; and a pusher having a lip presenting a relatively sharp edge at the bottom of its forward end and operative over the bottom portion of the throat toward 100 and from the needle for positively forcing the yarn under the hooks of the latter. 100

5. The combination in a knitting machine of a circular series of needles; a latch ring having a throat including an upwardly inclined bottom portion; a pusher having a yarn engaging lip operative over said bottom portion so as to be directed by the inclined part thereof under the yarn; with means for moving said pusher toward and 105 110 from the needles. 110

6. The combination in a knitting machine of a circular series of needles; a latch ring having a throat including an upwardly inclined bottom portion; a pusher having a 115 yarn engaging lip operative over said bottom portion so as to be directed by the inclined part thereof under the yarn; with means for moving said pusher toward and from the needles; the same including a reciprocable slide; and cam mechanism for operating said slide. 120

7. The combination in a knitting machine of a circular series of needles; a latch ring having a throat including an upwardly inclined bottom portion; a pusher having a 125 yarn engaging lip operative over said bottom portion; means for moving said pusher

toward and from the needles; the same including a slide operative in the throat of the latch ring and having slots enlarged at their rear ends; retaining pins extending across 5 the throat of the latch ring and passing through said slots; with means for moving the slide and the pusher toward the needles while permitting the front end of said slide with the pusher to move upwardly as the latter passes over the inclined bottom portion 10 of the throat.

8. The combination in a knitting machine of a circular series of needles; a guide for serving yarn to said needles; a latch ring 15 having a throat formed to hold the yarn in an elevated position; a yarn pusher operative in the throat and having a portion movable under the elevated part of the yarn; with means for moving the yarn pusher 20 toward and from the needles.

9. The combination in a knitting machine of a circular series of needles; with a yarn pusher movable toward and from said needles and consisting of a bar having one side 25 and the upper corner of its end cut away to

provide a relatively thin, substantially horizontal yarn engaging lip; with means for actuating said bar.

10. The combination in a knitting machine of a circular series of needles; a guide 30 for serving yarn to said needles; a latch ring having a curved, inclined bottom formed to hold the yarn elevated as it passes from said yarn guide; a yarn pusher having a portion movable under the elevated portion of the 35 yarn; and means for actuating said pusher to move it toward and from the needles.

11. The combination in a knitting machine of a circular series of needles; a guide 40 for serving yarn to said needles; a latch ring having a throat formed with an upwardly inclined bottom having a portion spaced away from the yarn as it passes from said guide; with a yarn pusher having a relatively thin, substantially horizontal lip movable 45 between the yarn and the inclined portion of the bottom of the throat; and means for moving said yarn pusher toward and from the needles.

ELMER U. AMES.
